UNITED STATES PATENT OFFICE.

DAVID D. GOOD, OF PHILADELPHIA, PENNSYLVANIA.

AUTOMATIC SPEED CONTROL AND RECORDING DEVICE.

1,288,870.

Specification of Letters Patent. Patented Dec. 24, 1918.

Application filed January 28, 1915. Serial No. 4,945.

To all whom it may concern:

Be it known that I, DAVID D. GOOD, a citizen of the United States, residing at 6203^b Jefferson street, in the city of Philadelphia and State of Pennsylvania, have invented certain new and useful Improvements in Automatic Speed Controls and Recording Devices, of which the following is a specification, reference being had therein to the accompanying drawings.

My invention has relation to automatic speed control of trains, trolley cars or other vehicles running on rails, and the recording of their rate of speed, stops and the duration of them.

My invention has for its object the provision of a device which will, when used in conjunction with a tripping device, reduce the speed of or stop a train or other vehicle and record the variations in the rate of speed at which it travels, time of stops, their duration and whether or not they were made by the engineer or by the device, without his volition, by contact with a suitable tripping device.

My invention consists in the novel construction, combination and arrangement of parts hereinafter described.

Throughout the accompanying drawing similar figures indicate similar parts.

Figure 1 is a front elevation of the vehicle equipments of the speed control and recording devices.

Fig. 2 is a plan view of the worm drive.

Fig. 3 is a plan view of one of the governor weights.

Fig. 4 is a plan view of the control contact lever.

Fig. 5 is a plan view of one of the rowel recorders.

Fig. 6 is a horizontal cross section on the line X. Y. Figs. 1 and 7.

Fig. 7 is a side elevation.

Fig. 8 is a cross section through the re-corder on the line A. B. Figs. 1 and 7.

Fig. 9 is an elevation of stop and control lever pivots.

Fig. 10 is a vertical cross section of the accelerating valve controlling the escape of air from the brake line.

Fig. 11 is a partially assembled perspective view of my device.

Fig. 12 is a perspective view of the elevating bar.

Fig. 13 is a perspective view of the oscillating lever.

Fig. 14 is a perspective view of the base bar 28.

Fig. 15 is a front view of a locomotive with my device attached.

1 is a valve block of substantially rectilinear form having hollow columns 2 and 3 attached to it or formed integral with it. 4 is a brace or web attached to the columns 2 and 5 and serving to carry the upper ball bearing 65 of the governor.

5, 6 and 7 are horizontal webs formed as part of the valve block 1 and support the stop and control levers, pinions and oscillatory mechanism of the trip control and stop valves.

The table 8 is formed as a part of the valve block to support the lower ball bearing of the governor stem, and the worm drive shaft 48 through its adjustable ball bearings 75 and 47.

A lever consisting of the shank 10, having a square opening 12 in a thickened or upset member of circular form, and the cams 11, 11, is designed to slide vertically on the pivot 21. For the sake of brevity this lever which is operated by a tripping device will herein-after be known as the control lever.

Fig. 6 shows a lever 13 of similar design and size. Through its upset or thickened member 14 is a square opening 16 which embraces the pivot 17 and is fastened thereto by the set screw 15. The cams 11' operate the stop valve. Thus, the upper lever will be known as the "stop lever".

The pivot 17, Fig. 9 is composed of four members. The upper one 19 is of square cross section design to carry a cross bar 41. The second member 18 is of round cross section so designed that it will turn freely in the web 7. A square member 17' fits the opening in the stop lever 13. The fourth or lower member is of round section, is half as long as the thickness of the web 6 wherein it turns and its diameter being greater than 100

that of the top member 24 of the pivot 21, it is adapted to rest on a shoulder in the web 6, immediately above the pivot 21.

The pivot 21 Fig. 9 is of square cross section throughout most of its length so as to allow the control lever to slide thereon. Its upper end 24 is of circular cross section and of length equal to half the thickness of the web 6 in which it turns. Immediately 10 below the square member is a cylindrical member 22 whose diameter is less than one side of the square member and of length equal to the thickness of the web 5. A square end member 23 extends below the web 5 and carries a cross bar 25.

25 is a cross bar having a square opening through its center adapted to engage the lower square member 23 of the pivot 21 and to be secured to it by a set screw 42'. The 20 ends of the bar may be chamfered and are bored at 26 and 26' so that the hooked ends of the springs 27 and 27' are engageable thereby.

The opposite ends of the springs 27 and 25 25 are attached to the lower rearward portions of the columns 2 and 3 at 27" Fig. 7.

On the upper square member 19 of the pivot 17 a similar cross bar 41 is attached by the set screw 42 and is provided with the spiral springs 40 and 40' which in turn have their opposite ends attached to the valve block.

The action of the spiral springs 40 and 40', 27 and 27' restores the contact levers to their normal position after they have been turned by a tripping device.

38a is an oscillating lever provided with a convex surface 38' to be acted on by the cams 11 on the control contact lever. On or near the center of this oscillating lever 38a, Figs. 6 and 13, a vertical barrel member 39' is formed, of length equal to the distance between the webs 5 and 6, Fig. 1, between which it turns on a pivot or pin 39". The said fin has an enlarged threaded head 45 which passes through the web 7 and screws into the web 6.

The opposite end of the oscillating lever 38a is provided with flat prongs 107. These prongs have openings of triangular or pentagonal form 107a, a point thereof directed backward toward the valve block.

32' is a valve rod with one end 31' flattened into a substantially rectilinear form having a triangular or pentagonal opening 55 which registers with the opening in the fork of the oscillating lever, the point directed outward or in an opposite direction to the point of the openings in the oscillating lever.

60. A pin 34', of diamond or rhombohedral cross section, which has a large flat head 33 is passed downward through the openings just described and is held in place by a cotter pin.

It will be seen that a pin 34' of this form 65 and that of the openings through which it passes, will couple the oscillating lever and the valve rod together and will act as a link and compensate for the difference in direction of motion between the oscillating lever 70 and the valve rod, allowing the latter to be drawn straight outward by the oscillating lever when it is turned through an arc on its pivot 39".

The control valve on the right is formed 75 and operated by the control lever in a similar manner to that of the stop valve just described.

The base of the governor is circular in form. Its perimeter is provided with teeth 80 43 Fig. 1, cut to register with the worm 45 on the shaft 48. Its under surface forms the cover of a ball bearing which rests in the cup 44. The cup 44 is screwed into the opening 44' of the table 8. Attached to the circular 85 base are wings 49 and the governor shaft 50. To the upper end of the governor shaft is attached a cone which revolves in the opening 61 of the elevating bar 62, on the balls held by the cup and adjustment 65.

To the wings 49 of the governor base are pivotally attached two weights 51 and 51' by bolts through the said wings and the eyes 52 and 52' of the weights. Slots 53" in the outer edge of the governor weights embrace 95 the lower ends of the rods 57 and 57' through which they are pivotally bolted by the bolts 53 and 53'. The opposite ends of these rods are, in turn, pivotally attached at 58 and 58' through their eyes and eyes 100 formed in the swivel block 59.

Lugs 54 and 54' on the governor weights are slotted at 56 and 56', Fig. 3 to engage the eyes on the tension spring 55 and 55'.

The swivel block 59 slides vertically on 105 the governor shaft and revolves with it, turning freely in the elevating bar 61 on ball bearings which are adjustable by the cone and nut 60.

The outer end of the drive shaft 48 is carried by the ball bearings 9' and 46 which are supported by the sleeves 9 and 47 on the table 8. The inner or opposite end of the shaft 48 is geared to the pony wheel shaft of the locomotive so that it will be driven 115 at a proportionate speed thereto by the toothed wheels 113 and 113'.

It will be seen that as the engine increases its speed the action of the governor will be to lower the swivel block 59 and the bar 61 120 and that as the speed of the locomotive decreases the tension springs 55 and 55' will draw the governor weights toward each other thus raising the elevating bar 61.

The elevating rods 66 and 66' have their 125 thickness increased and are threaded where they pass through the holes 64b and 64b' in the elevating bar. Their position relative

to it is fixed and regulated by the nuts 63 and 64. 68 and 69, 68' and 69' are guides which are attached to the columns 2 and 3. Spiral springs 67 and 67' rest on the guides 68 and 68' and bear upward on the elevating bar 61, to balance the weight of the parts attached thereto.

To the lower extremities of the elevating rods 66 and 66' is a base bar 28 whose central portion is provided with the ears 29 and 29' which embrace the control lever and cause it to slide vertically on the pivot 21. Between the said ears there is a round hole sufficiently large to allow the square pivot 21 to turn freely therein.

The ears 29 and 29' embrace the control lever 10 in such a manner that it may be turned to either side and that it will be raised or lowered on the pivot 21 accordingly as the governor acts on the elevating bar 61.

The guide rods 106 and 106' have their upper ends enlarged and threaded. Their lower ends are also threaded and have the same number of threads to the inch. They are of sufficient length to reach through the webs 5 and 6 into which they are screwed and serve to strengthen them as well as to act as guides for the base bar 28, which slides vertically on them as they pass through holes 29a and 29b in the ears 29 and 29'.

The column 3 is hollow forming the passage 75 which extends downward connecting with the horizontal passages 79 and 80. Connected with the passage 79 is a vertical passage 37 leading upward to the stop valve on the left, Fig. 1. The passage 77 leads away from the stop valve across to and is connected with the passage 76 in column 2 through the passage 79'.

The passage 80 connects with the passage 78 which leads to the control valve on the right. From thence the passage 80' leads to the passage 76 in column 2.

Both columns 2 and 3 terminate in air hose connections at their upper ends 81 and 81'. Column 3 is connected to the air brake line in that system of air brakes in which the air is allowed to escape or exhaust when the brakes are set. It is connected to the air storage tank where compression acts to set the brakes.

Column 2 in the exhaust type of air brakes may be connected with an auxiliary throttle Fig. 15, 33a by the flexible hose 20a and the flexible pipe 20a', or some similar device or the air may be allowed to escape from the column directly into the atmosphere.

In the compression type of air brake column 2, would be connected with the air brake line.

A screw accelerating valve consisting of a barrel and seat 82, Fig. 10, having ports 75, a threaded plunger 83 with a hexagonal head and a nut 85 and a packing ring 85', is

placed in column 3. On the hexagonal head 65 which allows for adjustment, is a forked handle 84 held in place by the nut 85. Its forked end embraces one end of the link 87. The opposite end of the link 87 is pivotally attached to the elevating bar through the 70 eyes 88.

The valve under discussion is set so that it is never quite closed. It will be seen that as the locomotive slackens speed this valve will gradually open.

Hinged to the face of the valve block 1, at 103, is a drop latch 101 which, when the oscillating bar 38' is acted on by the control lever and the valve opens, will drop behind the oscillating bar and prevent the valve 80 from closing. This downward action is assisted by the weight 100 and the spring 102. As the speed of the engine decreases, the base bar 28 is raised in the manner already explained. An adjustable set screw 99 is 85 affixed to the base bar 28 in such a position that when the train slows down to a given speed the head of this set screw will come in contact with and raise the latch 101 allowing the control valve to be closed by a spring 90 similarly placed to the spring 74 Fig. 6 on the stop valve mechanism.

The latch 100' acts in a similar manner to the one just described but is adjusted so that the train will have to come to a full stop as 95 the set screw 99' releases the latch 100' on the stop valve mechanism.

Between the columns 2 and 3 a metal housing, shown in Figs. 1 and 8, is placed. The face of this housing 89 has a vertical slot in 100 its center and is removable and adapted to be locked or sealed in place.

Within the housing is a roller 90, Fig. 8, on which a strip of paper is wound. The rollers 91, 92 and 93 are in close proximity to 105 each other and are geared together and driven by simple clock work regulated by escapement.

The roller 94 is driven by a separate spring in such a manner that when the strip of 110 paper wound on roller 90 is led around 91 between it and 92 around in front of 92 then between it and 93 and attached to the roller 94 it will be wound on the latter as fast as it is fed through the rollers 91, 92 115 and 93.

A flat spring 96, Figs. 7 and 8 is adjustably attached to the elevating bar 61 and carries a recording point 95 on its free upper end. This recording point bears on a strip 120 of paper passing around the roller 92.

The strip or ribbon of paper before referred to is ruled horizontally and vertically. The recording point being attached to the elevating bar 61 will move in a vertical line 125 according to the variation in speed of the locomotive. The horizontal ruling on the ribbon will refer to the rate of speed. The

vertical ruling will be so placed as to require a given number of minutes for each division to pass the recording point. Thus it will be seen that the line drawn by the recording point will indicate the variation in speed, the stops and the length of time any rate of speed or stop was maintained. A notation of time made on the ribbon at the time the clock work was started will make a complete record of the trip.

The vertical rod 70 is held in place by, and turns in, the lugs 71 and 108 which are attached to the sides of the valve block 1 and the column 2. A horizontal L rod 72 is permanently attached to the vertical rod 70. The unattached end of its longer member reaches sufficiently far across the face of the valve block to extend behind the free end of the oscillating lever 38 so that when the latter is turned on its pivot this horizontal rod will be pushed backward toward the valve block.

Near the top of the rod 70 a horizontal bar 97 is attached which carries on its opposite and forked end a rowel 98 in a horizontal position. The bar 97 is of proper length to allow the rowel to strike the roller 92 through the slot in the housing of the recording mechanism which it will do when the stop lever 30 is turned, as will be readily seen.

The vertical rod 70', with its horizontal bars 72' and 97' which is held in position on the opposite side of the valve block by the lugs 71' and 108' is acted on by the controlling mechanism in the same manner as the one just described.

The roller 92 in the recording mechanism is provided with rings of soft elastic material 109 set in each of its ends above and below the limit of travel of the recording point.

The rowels 98 and 98' are so placed as to strike the record ribbon over these rings thus perforating it and so indicating when the train was stopped or its speed reduced by the action of a tripping device on the mechanism herein described.

Fig. 15 is illustrative of the device as it is attached to a locomotive and shows its relative position to a tripping device placed adjacent the tracks. The stop 8t is the only part of the tripping device necessary to be considered. It is shown here in a position to operate the control lever 10 and cause the train to be slowed down to a cautionary speed. 48 is the shaft geared to the pony wheel shaft through the medium of the gears 113 and 113'. 14X refers to the adjustable method of attaching the hanger 13X to the truck. The hose connection 19X leads from the air brake line to column 1. On opening the stop or control valves, the air flows through the hose and pipe connection 20X' to the cylinder 30X where it drives forward a piston connected to the shuttle valve 33X

and closes the said valve in the main steam line 34X. The lever 37X is shown raised in the position in which it is used to manually restore the auxiliary throttle to its normal open position.

It is to be understood that necessary protection may be given to the parts of this invention by a suitable housing.

Operation.

It is understood that this mechanism is to be used in connection with a tripping device of suitable construction such as the one described in my application for Letters Patent No. 719,830 filed September 11, 1912, and No. 835,652 filed May 1, 1914. The latter may be modified to assume three positions.

My speed control and recording device is attached by bolts, screws or other means of support through the valve block and by means of bands around the column to the forward or pony wheel truck of a locomotive where it will be carried parallel to and at a fixed distance from the rail.

The drive shaft having been connected by proper gearing to the pony wheel shaft of the locomotive, the necessary adjustment made for governor speed, height of elevating bar, speed at which valve-release latches are tripped by the adjusting set screw and for the regulating of clock work in the recording mechanism, it is assumed the train is beginning to move forward.

As the rate of speed of the train increases the worm drive shaft will turn the governor at a relatively increasing speed which will cause the weights to swing outward by centrifugal force and lower the elevating bar proportionately. The recording point attached to the elevating bar will describe a downward curve on the record ribbon.

The accelerating screw valve whose lever handle is attached by a link to the elevating bar will gradually approach a closed position.

The elevating rods will lower the base bar attached to them which in turn will move the control lever downward. As the train approaches its limit of speed my device will assume the position shown in Figs. 1, 7 and 10.

Should the engineer attempt to pass a green or cautionary signal and a tripping device is set at a proper height to operate or turn the control lever, the turning of this lever will cause the cams on its base to rock the oscillating lever which will in turn open the control valve. The valve having reached its open position the latch will drop and hold it open. The spiral spring through the medium of the cross bar will immediately return the control lever to its normal position.

As I have assumed the train to be moving at high speed, the accelerating valve in the

column 3 will be almost but never quite closed. The control valve being thus opened the air under compression in the brake line and cylinder will be allowed to flow slowly 5 through the accelerating valve in column 3, downward through passage 75, forward through passage 80, across the valve block through passage 78 to the control valve then backward through 80' and upward through 10 passage 76 in column 2.

From the top 81 of column 2 the air may be allowed to escape, thus setting the air brakes or it may be conducted by a hose connection and proper piping to a shuttle valve 15 and auxiliary throttle.

The accelerating valve being open in inverse proportion to the speed of the train, the brakes will be set gradually with increasing force and so eliminate the usual 20 shock and sliding of the wheel.

As the speed of the train is reduced the control lever will be raised on its pivot by the base and ears embracing it. Coincidentally the adjusting set screws in the base 25 bar will approach the weights on the latches. When the speed of the train has been reduced to a predetermined point the latch will be raised and release the control valve which will be closed by its spring. The 30 brakes will be released by air from storage tank or pump. If an auxiliary throttle is in use it may now be opened by the engineer.

The oscillating rod 38' which operates the control valve has a wider face and same 35 cross section as the one shown in Fig. 6. As the speed of the train is reduced to a determined rate the control lever will be raised above the face of the oscillating rod so that the cams 11 will not contact with it. Thus 40 it will be seen that should the control lever strike and be turned by a tripping device while the train is running at a safe rate of speed the brakes will not be set. In ordinary practice the tripping device would not 45 be high enough to reach the control lever when it is at this point.

When a danger signal is set against a train and it is desired to stop it, the trip is set sufficiently high to turn the upper or stop 50 lever.

The stop lever operates to open the stop valve on the left in the same manner as the control lever operates the control valve.

The accelerating valve performs its function in the same way admitting the air 55 through passage 75 to 79 then up through 37 to the valve. The stop valve being open it enters passage 77 crosses the valve block to 79 and thence through the passage 76 in 60 column 2 to the open air or auxiliary throttle. The stop valve is released and closed as the train comes to a stop in the manner already described.

Having thus described my invention, I

claim the novelty of the following combinations: 65

1. In automatic speed control apparatus, the combination with an air brake line, tripping devices adjacent the track, a valve block having air passages communicating 70 with the air brake line, a control valve in an air passage of said valve block, a valve operating lever, a vertically adjustable and horizontally movable control lever adapted to actuate said valve operating lever and to 75 be moved horizontally by said tripping devices, of a governor actuated by an axle of the train and connected to said control lever so as to vertically adjust the same in accordance with the speed of the train, a stop valve 80 in an air passage of said valve block, and a second valve operating lever, a horizontally movable stop lever adapted to actuate said second valve operating lever and adapted to be moved horizontally by said tripping devices. 85

2. In automatic speed controlling and stopping apparatus for trains, the combination with an air brake line on the train and tripping devices adjacent the track, of a 90 valve block having a main passage communicating with the air brake line and having branch passages, a control valve and a stop valve arranged respectively in the branches of said passage, an accelerating valve arranged in said main passage, valve operating levers connected to said control and stop valves respectively, control and stop levers to actuate said valve operating levers and adapted to contact with the tripping 100 devices, a governor carried by the valve block and actuated by an axle of the train, said governor being connected with and adapted to adjust the control lever and operate the accelerating valve. 105

3. In automatic train stopping and controlling apparatus, the combination with the air brake line of a train and tripping devices adjacent the track, of a valve block 110 having air passages communicating with the air brake line, stop and control valves in said passages, stop and control levers for operating said valves, arranged and adapted to be moved by the tripping devices, said control lever being vertically adjustable on its pivot, a governor geared to an axle of a train vehicle, means for raising and lowering said control lever through the action of the governor, means for transmitting movement to the control valve from the control lever and means controlled by the governor for temporarily holding said valve open and for automatically closing the same. 115

4. In automatic speed controlling apparatus for trains, the combination with an air brake line, tripping devices adjacent to the track and means for controlling the passage of air through said line to stop the 120 125

train and reduce its speed, operable by said tripping devices, of an auxiliary valve in the air passage of said brake line, arranged and adapted to be opened to increase the supply of air through the brake line, a governor driven by an axle of the train and connections between the governor and the auxiliary valve to operate the same.

5. In automatic speed controlling apparatus for trains, the combination with an air brake line, tripping devices adjacent to the track, valves in said brake line to control the passage of air, one of said valves being a control valve, of a governor driven from an axle of the train, a vertically sliding lever connected to and moved vertically by the governor, control-valve operating means arranged and adapted to be actuated by the control lever, means for locking said valve operating means in position when the valve is open and means for unlocking the same.

6. In automatic speed controlling apparatus for trains, the combination with an air brake line on the train and tripping devices adjacent the track, of a valve block comprising vertical columns and transverse connections with air passages communicating with the air brake line, a governor receiving motion from an axle of the train, an elevating bar connected to and arranged and adapted to be raised and lowered by the governor, vertical rods attached to said bar, a horizontal base bar carried by said rods, a control lever carried by said base bar and arranged and adapted to be turned horizontally by the tripping devices and guides carried by said column through which said rods slide, a valve in said air passages and valve operating means connected with said governor.

7. In automatic speed controlling apparatus for trains, the combination with an air brake line, of a valve block having air passages communicating with the said air brake line, valves in said air passages, supporting guides, vertical rods sliding in said guides, a governor, an elevating bar to which said governor is swiveled and through said rods pass and are adjustably attached, spiral springs surrounding the vertical rods and bearing upwardly against the elevating bar, control and stop levers and associated mechanism for operating said valves, one of said levers being connected to the elevating bar and tripping devices for operating said levers.

8. In automatic speed controlling apparatus for trains, the combination with an air brake line, of a governor geared to a shaft of a vehicle of the train, a valve block, having passages communicating with said air brake line, a control valve seated therein, an oscillating lever attached to the spindle of

said valve, a vertically movable control lever pivotally attached to the valve block and having cam projections adapted to turn said oscillating lever and open said valve and tripping devices for horizontally moving said lever.

9. In automatic speed controlling apparatus for trains, the combination with an air brake line of a valve block having air passages and valves therein, a governor, an elevating bar controlled by said governor, a base bar coupled to said elevating bar, a control lever, a pivot on which said control lever is raised and lowered in proportion to the speed of the governor, means for opening one of said valves by the horizontal movement of said control lever and tripping devices for horizontally moving said control lever.

10. In automatic speed controlling apparatus for trains, the combination with an air brake line, of a valve block having air ports and passages and valves therein, a governor, a base bar which is raised as the speed of the governor is decreased, a stop lever, a control lever mounted on said base bar, adjustable set screws in the base bar and drop latches adapted to hold said valves open and to be raised by the set screws as the speed of the governor is increased.

11. In automatic speed controlling apparatus for trains, the combination with an air brake line, of a valve block having passages communicating with said line and valves therein, valve operating mechanism, control and stop levers adapted to be operated by tripping devices adjacent the track, and to operate the said valve operating mechanism, a governor for vertically moving said control lever, pivots on which said levers turn, and springs connected to the cross bars to restore the levers to their normal positions after having been tripped.

12. In automatic speed controlling apparatus for trains, the combination with an air brake line and a valve block having air passages, of a governor geared to the shaft of a train vehicle, a control lever arranged and adapted to be moved vertically by the governor, a stop lever whose height is fixed, stop and control valves in the air brake supply operated by the said levers and arranged and adapted to allow the air from the brake line to escape, tripping devices adapted to operate said levers and an accelerating valve between the stop and control valves and the brake line, arranged and adapted to be operated by the governor to control the escape of air and set the brakes gradually.

13. In automatic speed control apparatus, the combination with an air brake line, tripping devices adjacent the track, a valve block having air passages communicating with the air brake line, stop and control

valves in the air passages of said valve block, valve operating levers, a vertically adjustable and horizontally movable control lever adapted to actuate one of said valve operating levers and a second horizontally movable lever, adapted to actuate the other of said valve operating levers; of a governor actuated by an axle of the train and connected to said control lever so as to vertically adjust the same and a recording device having 10 marking devices connected respectively to the governor, to the control lever, and to the stop lever.
